UNITED STATES PATENT OFFICE.

NEVIL MONROE HOPKINS, OF WASHINGTON, DISTRICT OF COLUMBIA.

CARD GAME.

977,010.

Specification of Letters Patent. Patented Nov. 29, 1910.

Application filed June 25, 1910. Serial No. 568,915.

To all whom it may concern:

Be it known that I, NEVIL MONROE HOPKINS, a citizen of the United States, residing at Washington, in the District of Columbia, 5 have invented certain new and useful Improvements in Card Games, of which the following is a specification.

This game is played with a set of cards of two different colors. On each card is 10 printed the name of some personal qualification or characteristic, its specification or definition, and a numeral or numerals indicating the fixed or graded value to be allotted to such qualification. Accompanying the 15 set of cards is a scoring device consisting of a triangular figure, having at its sides inclined scales of different colors, corresponding to those of the cards, and a vertical central scale.

20 Referring to the accompanying drawings: Figures 1 and 2 are face views of two cards of the set; Fig. 3 is a face view of the scoring diagram; and Fig. 4 is a face view of two scoring disks.

25 The card shown in Fig. 1 bears the title "State reputation," and its specification or definition, to wit, "Must have your name well known throughout the State as a result of meritorious activity." This card would be 30 colored yellow and bears a numeral 5, indicating the assumed value of "State reputation," as defined.

The card shown in Fig. 2 bears the title "Well read," and the specification, "One 35 conversant with standard and modern literature and able to talk about it with intelligence and without pedantry." This card would be colored green and bears the numerals 1-5, indicating the graded value as 40 signable to the qualification.

The entire set or pack of cards consists of equal numbers of yellow and green cards. The specifications are original definitions written for this game by competent authorities, and the name and occupation or attainments of each authority are printed on the 45 card beneath the definition furnished by him.

The scoring device shown in Fig. 3 is a figure in the general form of an isosceles 50 triangle, with a horizontal base, the sides of the triangle being stepped and the tops of the steps being joined by horizontal lines, to suggest a pyramid to be climbed by the aspirant for honors in the game. At 55 each side of the diagram or figure is an inclined scale, here numbered from 0 to 145.

The lefthand scale is marked "Yellow" and the righthand scale "Green." At the center of the figure and bisecting the triangle is a vertical scale, here shown as a ladder, bearing the numerals 0 to 100.

60 Yellow and green disks, shown in Fig. 4, are also provided, bearing numerals corresponding to those on the cards.

The qualification of each player in the 65 subject named on each card is determined in accordance with the specification printed thereon, and the player is then given a counter or disk bearing a numeral with the value assigned thereto. The right of the 70 player to score may be determined either by himself or by the other players, as agreed, and the value assigned to the player in the subjects named on the graded cards depends on the extent of his attainments therein. 75 The award of scores or counters for certain test cards may be conditioned on the actual demonstration by the player of his possession of the several qualifications named thereon, for example he may be required to 80 prove that he is able to play the piano or to read a foreign language, judgment being passed on his proficiency by the other players.

In playing the game, each participant successively reads, or has read to him by a 85 dealer, the specifications either on the entire set of cards, or on as many cards as have been taken for use in the game. If he is adjudged qualified in the subject of any 90 particular card, he is awarded a counter bearing the number printed on that card to denote the value of such subject, or, in case of a graded-value card, is awarded a counter with a numeral corresponding to the extent 95 of his qualification in its subject.

When the set of cards has been played through and each player has received yellow and green counters for all of the values awarded to him, the score of each player is 100 ascertained by adding the numbers on his yellow counters and noting or marking the total on the yellow scale of the scoring diagram; then adding the numbers on his green counters and noting or marking their total 105 on the green scale; and finally joining the two noted points on the yellow and green scales by a cord or straight-edge, whereupon the final score is read on the vertical central scale, at the point intersected by the cord 110 or straight-edge, in parts per hundred or percentage.

The game may be played as "solitaire" by one person, or by any number of persons.

I claim:

1. A card game, comprising a set of cards, 5 each card having printed thereon the name of some personal qualification and the specification and a numeral indicating the value thereof.
2. A card game, comprising a set of cards 10 of two different colors, each card having printed thereon the name of some personal qualification and the specification and a numeral indicating the value thereof.
3. A card game, comprising a set of cards 15 of two different colors, each card having printed thereon the name of some personal qualification and the specification thereof, some cards being numbered with a fixed value and the other cards numbered with 20 graded values.
4. In combination with a set of cards, each card having printed thereon the name of

some personal qualification and the specification and a numeral indicating the value thereof, a scoring device consisting of a triangular figure having inclined scales at its sides and a vertical central scale. 25

5. In combination with a set of cards of two different colors, each card having printed thereon the name of some personal qualification and the specification thereof, some cards being numbered with a fixed value and other cards being numbered with graded values, a scoring device consisting of a triangular figure having inclined side scales 30 of different colors, corresponding to those of the cards, and a vertical central scale. 35

In testimony whereof, I affix my signature in presence of two witnesses.

NEVIL MONROE HOPKINS.
